HOOK LOCK

William A. Cole, Detroit, Mich.

Application August 10, 1951, Serial No. 241,211

1. Claim. (Cl. 292—108)

This invention relates to a lock for a hook and eye, such as is conventionally used for retaining in either closed or open position, a window sash, screen sash, or door.

In conventional hook and eye applications, there is always the possibility of the hook becoming disengaged from the eye, either accidentally or by design, as for example, when an intruder attempts to obtain entry into a building. As will be appreciated, it is a relatively simple matter for an intruder to extend a wire or other thin object through a door or window screen, in a manner to pull the hook out of engagement with its associated eye, thus to unlock the door.

It is, accordingly, an important object of the present invention to provide a lock means for a hook and eye, which can be adjusted to selected positions in one of which it will be operative to prevent disengagement of the hook from the eye, and in another of which it will permit withdrawal of the hook in the usual manner.

Another important object is to provide a lock means of the type stated which is adaptable to any conventional hook and eye device, without necessity of modifying said device in any manner.

Another important object is to provide a lock for a hook and eye which will be of very low cost, and which will comprise a minimum of parts simply arranged in a manner to impart to the lock the characteristic of ruggedness.

Yet another object is to provide a lock for a hook and eye that is operatively positioned merely by insertion of the shank of the eye through an opening formed in said lock, this having the effect of mounting the lock rotatably upon the shank when the shank is threaded into a supporting surface such as a door jamb or window sill.

Referring to the drawings:

Figure 1 is a fragmentary perspective view of a window and of a pair of devices formed in accordance with the present invention, one of said devices being positioned operatively and the other being positioned inoperatively;

Figure 2 is a top plan view, on an enlarged scale, of one of the lock devices operatively positioned in relation to a hook and eye, a screen sash and window sill being illustrated fragmentarily;

Figure 3 is a sectional view taken on line 3—3 of Figure 2 and,

Figure 4 is an exploded perspective view of the lock device.

Referring to the drawings in detail, I have

illustrated the lock device as applied to a conventional double hung window including side jamb casings 1, a sill 2, a window sash 3, and a screen sash 4. It will be understood, however, that the lock device constituting the present invention is equally applicable to other types of windows, interior or exterior doors, cupboard doors, and the like.

A lock member forming a part of the locking device is generally designated 5, and includes a flat, rectangular base 6 having near its center an opening 7 extending therethrough. The opening 7 is slightly offset from the center of the base 6, that is, it is disposed closer to one end of the base than to the other, though being positioned upon the longitudinal center line of the base.

That end of the base to which the opening 7 is closed is integrally formed with an upstanding flat abutment 8 extending the full width of the base, and disposed at right angles to the base. The abutment and base thus form an L-shaped lock member 5 including a base portion, and a leg, said leg being the abutment 8, integral with and upstanding at right angles from one end of said base portion.

On the exterior surface of the abutment 8 is formed, medially between opposite sides of the abutment, a gripping handle 9, extending outwardly from the abutment so as to afford a convenient grip for shifting of the abutment between operative and inoperative positions respectively.

Overlying and underlying the base are washers 10 and 11, having center openings registering with the opening 7 of the base. The washer 10 is of unbroken formation, as readily seen from Figure 4, while preferably, the washer 11 is of split formation.

A screw eye 12 is of conventional formation, for use with a conventional hook 13 adapted to be secured to a supporting surface such as the screen sash 4 by a screw eye 14. The screw eye 12 is formed with the usual eye portion and shank, and the shank is extended through the openings of the washers and base, and is threaded into an adjacent supporting surface, such as the sill 2 of the window. The washer 11 spaces the base 5 slightly above the surface of the sill, thus to permit the base to freely rotate upon the shank of the screw eye, without possibility of marring the surface of the sill. The screw eye, as may be noted from Figure 3, is threaded into the sill 2 to an extent as will cause the eye portion to bear against the upper washer, to such an extent as will still permit the base to be freely

rotated upon the shank, while still being retained firmly in a plane perpendicular to the longitudinal center line of the shank.

As may be noted, this relative arrangement of parts is one that permits a user to grip the handle 9, and swing the abutment 8 in an arcuate path about said axis of rotation, between one position in which it extends across the path of swinging movement of the hook 13, thus to prevent the hook from becoming disengaged from the eye portion, and another position in which it is inoperatively located, to allow conventional use of the hook and eye.

In Figure 1, the lock means shown at the right is operatively positioned to prevent separation of the hook from its associated screw eye, while the lock device at the left in this figure is inoperatively positioned. The arrow indicates the direction of rotation of the lock device, whereby, after the hook 13 has been entered in the screw eye 12, the lock device can be swung around across the path through which the hook normally swings in being withdrawn from the eye, thereby to securely restrain the hook against disengagement.

It may be noted that when the abutment is operatively positioned (Figure 3), it lies in a plane parallel to and laterally spaced from the plane in which lies the eye portion of the screw, and is so spaced from said eye portion as to cause the hook 13 to be held substantially against movement, between the eye portion and abutment.

It is important to note that the device is one which permits its application to hook and screw eye assemblies, where ever said assemblies may be used. Whenever the device is used as a lock for a hook of this type, it does not interfere with placement of the hook for swinging movement in any selected plane which the user may find most desirable. For example, in the illustrated application of the invention, the hook is swingable into and out of the eye portion through a plane oblique to the longitudinal axis or center line of the screw eye, about which the abutment rotates, said plane of swinging movement of the hook also being oblique to the plane of the base of the lock device. In other hook and screw eye applications, the hook might be swingable through a plane perpendicular to the axis of the screw eye, and in still other applications it might be swingable in a plane in which the screw eye is wholly disposed. In any of these arrangements, the lock device will still operate with full efficiency. Thus, the device does not in any way restrict the user from applying the hook and eye in the location and ar-

rangement he may find most suited to his particular purpose, and further, the device permits the use of a thoroughly conventional, unmodified hook and eye such as may be purchased in any commercial establishment in which hardware and related products are sold.

What is claimed is:

A lock for a hook and screw eye having a shank and an eye portion in which the hook is engageable, comprising a flat base located in a plane perpendicular to the longitudinal center line of the screw eye and having a center opening receiving said shank for rotation of the base thereupon, said base being spaced longitudinally of the screw eye from said eye portion; an abutment rigid with said base and spaced from the axis of rotation thereof, said abutment extending from the base in laterally spaced, parallel relation to said eye portion and being swingable on said axis through an arcuate path about the eye portion, between positions in one of which it extends across the path through which the hook is swingable when being withdrawn from the screw eye and is operative to restrain the hook against disengagement from said screw eye, and in the other of which it is disposed clear of said path and is inoperative to prevent said disengagement, the base and abutment being integrally joined at right angles to one another to form a lock member of L-shaped formation the upstanding leg of which is defined by said abutment and lies in a plane parallel to the plane in which the eye portion lies, said planes of the eye portion and abutment being so spaced as to engage the hook substantially against movement therebetween when the abutment is in the first-named position thereof, the eye portion of the screw eye being substantially greater in diameter than the diameter of the center opening of the base; a washer circumscribed about the shank of the screw eye between the base and eye portion and so proportioned as to thickness as to be engageable frictionally by said eye portion bearing downwardly thereagainst; and a second washer underlying the base so as to be interposed between said base and a surface to which the shank is secured.
